ANIMAL FIGURE

Anne Ruth Lipman, Newton, Mass.

Application February 9, 1955, Serial No. 34,435

Term of patent 14 years

(Cl. D34—2)

Fig. 2.

Fig. 1.

Fig. 3.

Fig. 1 is a plan view of an animal figure showing my new design;

Fig. 2 is a front elevational view thereof; and

Fig. 3 is a side elevational view of the same.

The rear view is the same as the front view except that two, instead of three, petals are visible and the head has no face.

I claim:

The ornamental design for an animal figure, substantially as shown and described.
